Inventor:
Walter Wolff,
by *Walter S. Lantz*
His Attorney.

UNITED STATES PATENT OFFICE.

WALTER WOLFF, OF BERLIN-KOPENICK, GERMANY, ASSIGNOR TO GENERAL ELECTRIC COMPANY, A CORPORATION OF NEW YORK.

TELEPHONE REPEATER.

Application filed June 30, 1925, Serial No. 40,564, and in Germany July 12, 1924.

My present invention relates to a switching system for automatically connecting a telephone repeater and balancing networks between two long distance telephone offices.

5 One of the objects of my invention is to provide an arrangement whereby a selector may be operated in response to calling current to automatically control the closing of a heating current for the repeater tubes and 10 to automatically connect a calling and a called line to opposite sides of the repeater. A further object of my invention is to provide means for opening the heater circuit for the repeater tubes and for disconnecting 15 the calling and called lines at the close of the conversation.

The novel features which I believe to be characteristic of my invention are set forth with particularity in the appended claims.

20 My invention itself, however, will best be understood by reference to the following description taken in connection with the accompanying drawing in which Fig. 1 shows diagrammatically a tandem office V containing repeaters, and a plurality of stations 1-6 inclusive adapted to be connected to each other through office V and an idle repeater. Fig. 2 shows diagrammatically a circuit organization whereby my invention may be 25 carried into effect.

Referring to the drawing, I have designated a calling transmission line as F_2 and the called transmission line as F_4 . Two relays as R'_2 and R''_2 are associated with each line, the former being used when a party at 30 the end of the line is calling, and the latter relay being used when the party at the end of the line is called. Thus when line F_2 is calling F_4 the relays R'_2 and R''_2 are energized by means of a selector and the lines F_2 and F_4 are automatically connected across 35 an amplifier of the repeater V. At the same time, the lighting of the cathode element of the amplifying tube and the connection of the compensating or artificial lines Kl_2 and Kl_4 are effected by means of a selector 40 2. If other lines are to be connected with each other, relays which I have indicated at R'_3 , R''_3 and R'_4 and R''_4 may be employed to 45 effect the connection. As long as no impulses come over the line F_2 , the armature 50 a_2 of relay Gl_2 is at rest so that none of the three selector arms r' , r'' and r''' can take up a connection and the selector circuit is 55 not energized unnecessarily. Each selector

is provided with a disconnect relay R which brings the selector arms back to the zero position at the end of the call. Relay R'_2 is equipped with contacts g_2 , i_2 , f_2 , k_2 , l_2 , m_2 , while relay R''_4 has contacts m_4 , l_4 , k_4 , and i_4 . By means of these contacts, lines F_2 and F_4 , and the balancing networks Kl_2 and Kl_4 are connected.

The method of operation is as follows: If line F_2 is calling line F_4 , the operator at the end of line F_2 may send four impulses. The relay Gl_2 receives the four impulses and its armature a_2 is brought up four times. This closes the circuit of the selector relay WR_2 from the positive pole of battery B through armature a_2 and the winding of relay WR_2 to the negative pole of the battery. The selector relay now rotates the selector arms from the position of rest 0 to position 4. In parallel with the relay WR_2 is connected a slow release relay V_2 , which is energized at the same time that relay WR_2 is energized, but whose armature releases only a short time after the succeeding impulses. The armature of relay V_2 separates the two selector arms r' and r'' from the battery so that during the passing over of contacts 1-3 no false impulses of current result. After the release of the relay V_2 current flows from the negative pole of battery B over the filaments of the amplifier tubes to the relay U, relay R''_4 , line x_4 , line y_4 , contact r''_4 , arm r'' , point c_2 to the positive pole of battery B. This causes the armature of relay R''_4 to be attracted and to close a circuit from contact s_4 through relays R'_2 , arm r' and point c_2 to the positive pole of the battery. Energization of relay R'_2 causes the tube circuit to be closed from the negative pole of battery B through the filaments of the tubes, relay U, relay R''_4 , contact s_4 , relay R'_2 , contact b_2 and contact q of the slow-acting relay ZR to the positive pole of the battery. The relay R'_2 moves its contacts i_2 , k_2 to the active positions g_2 and f_2 , also, the contacts l_2 and m_2 are thereby moved into the active position. In this way the line F_2 , and the balancing network connected through Kl_2 , are connected over the wires IV and KIV to the amplifier or repeater V. The same procedure is true for the relay R''_4 which moves its contacts i_4 , k_4 , l_4 and m_4 into the active position. This connects the line F_4 and the balancing network Kl_4 to the repeater over IV and KIV . 110

In this manner the tubes are lighted and the connection is completed and it is possible to talk over the repeater. After the relay R'_2 has been operated, the release relay R receives current from the battery B through a circuit extending from point c_2 , through arm r' , contact e_2 and relay R to the negative pole of the battery. Energization of relay R returns the selector arms to their zero position. Relays R'_2 and R''_4 however remain connected to the battery B through contacts b_2 and s_4 .

When talking is finished a signal is sent over the line F_2 in order to disconnect the amplifier and lines. This current passes over contacts g_2 and f_2 of relay R'_2 and over the lines I^V and amplifier V to the slow acting relay ZR . Energization of relay ZR opens the filament circuit at q . At the same time relays R'_2 and R''_4 are deenergized so that their contacts return to the position of rest. The system of relays is then again ready for taking up a new connection.

If lines F_2 and F_4 are connected, it is impossible to connect either of these lines with another line. This is due to the fact that there are contacts y etc. on relay U for each line. When relay U is energized, these contacts disconnect the relay R'_2 from the middle selector arms and complete a connection with the third selector arms r''' from battery B , contact c_2 , selector arm r''' , contact y of the called line, selector arm r''' and relay ZR_2 to the negative pole of the battery B . Energization of the relay ZR_2 sends back in the customary manner a signal to the calling line and also brings the selector arms back to the zero position.

What I claim as new and desire to secure by Letters Patent of the United States, is,—

1. The combination in a telephone system of a plurality of transmission lines adapted to be connected through a thermionic amplifier, an artificial line associated with each transmission line, and means responsive to a calling current for closing a heating circuit for the amplifier cathode, and for connecting the artificial lines with their associated transmission lines.

2. A signaling system comprising a plurality of stations, a transmitting line connected to each station, a repeater adapted to be connected to said lines, said repeater comprising a thermionic amplifier, a plurality of relays associated with each transmitting line and adapted to connect that line to the repeater, one of said relays being energized when the line is calling, and another being energized when the line is called, and means comprising a slow-acting relay for deenergizing said first mentioned relays when a conversation is ended.

3. The combination in a telephone system of a plurality of transmission lines adapted to be connected through a thermionic ampli-

fier, means responsive to a calling current for closing a heating circuit for the amplifier cathode and also responsive to the same calling current for selectively connecting a calling station with any one of a plurality of remote stations.

4. The combination in a telephone system of a plurality of transmission lines adapted to be connected through a thermionic amplifier, means responsive to a calling current for closing a heating circuit for the amplifier cathode and also responsive to the same calling current for selectively connecting a calling station with any one of a plurality of remote stations, and means for preventing connection of a third transmission line with a busy line.

5. A signaling system comprising a plurality of stations, a transmission line connected to each station, a repeater adapted to be connected to said lines, said repeater comprising a thermionic amplifier, a plurality of relays associated with each transmission line and adapted to connect the transmission line to opposite sides of said repeater one of said relays being energized when the line is calling, and another of said relays being energized when the line is being called.

6. The combination in a telephone system of a plurality of transmission lines adapted to be connected through a thermionic amplifier, a selector responsive to a calling current for closing a heating circuit for the amplifier cathode, and for selectively connecting a calling station with any one of a plurality of remote stations, and means for returning the selector to an inoperative position when the selection has been effected.

7. In combination a plurality of stations, transmission lines connected to said stations, a repeater adapted to be connected to said transmission lines, said repeater comprising a thermionic amplifier, a plurality of relays associated with each line and adapted to connect said lines with said repeater, means comprising a selector for closing a heating circuit for the amplifier cathode and for controlling the connection of said transmission lines to said repeater, means for returning said selector to an inoperative position and means for thereafter controlling said cathode circuit and repeater connection.

8. In combination, a plurality of stations, transmission lines connected to said stations, a repeater adapted to be connected to said transmission lines, said repeater comprising a thermionic amplifier, a plurality of relays associated with each line and adapted to connect said lines with said repeater, a selector responsive to a calling current for effecting operation of certain of said relays to connect two of said transmission lines to said repeater, and means for returning said

selector to an inoperative position when the connection has been made without interrupting said connection.

9. In combination, a plurality of stations, transmission lines connected to said stations, a repeater adapted to be connected to said transmission lines, said repeater comprising a thermionic amplifier, a plurality of relays associated with each line and adapted to connect said lines with said repeater, a

selector responsive to a calling current for effecting operation of certain of said relays to connect two of said transmission lines to said repeater, and means controlled by a relay associated with a calling line for returning said selector to an inoperative position. 15

In witness whereof, I have hereunto set my hand this 15th day of June, 1925.

WALTER WOLFF.
